UNITED STATES PATENT OFFICE.

WILLIAM E. WILSON, OF MASON CITY, IOWA, AND HENRY G. LYKKEN, OF MINNEAPOLIS, MINNESOTA.

METHOD OF AND APPARATUS FOR DRYING REFRACATORY MATERIALS.

Application filed December 11, 1923. Serial No. 679,954.

To all whom it may concern:

Be it known that we, WILLIAM E. WILSON and HENRY G. LYKKEN, citizens of the United States, residing, respectively, at Mason City, Iowa, and Minneapolis, Minnesota, have invented certain new and useful Improvements in Methods of and Apparatus for Drying Refractory Materials, of which the following is a specification.

- 10 The present invention relates to the drying of refractory materials and wares, such as refractories, bricks, tiles, hollow tiles, floor tiles, building tiles, wall tiles, drain tiles, sewer pipes, products produced by the clay 15 and like industry, molded or model wares, pottery, porcelain, ceramic wares, rough clay wares, terra cotta, plastic and dry pressed material, and all other various and similar articles and substances, by the use 20 of heat and mechanism or apparatus for effecting such drying.

Among the objects of the invention are to dry refractory materials in a very short period of time without danger of the surface of the material cracking or checking, long periods of time together with a slow or gradual change in temperature heretofore having been required to avoid the objection of cracking or checking; to rapidly absorb and cause a rapid evaporation of the moisture within and on the surface of the materials or wares without the previously required exercise of the great care to prevent a rapid absorption and evaporation 35 which heretofore caused checking; to heat the materials in an atmosphere or surrounding mass of fluids or gases saturated or nearly saturated with a vapor, such as water vapor, preferably in the form of steam, to 40 a temperature slightly in excess of the boiling point of water, if water vapor be used; to almost or substantially balance or equalize the vapor tension at the surface of the materials so that in the interior of the materials 45 in order that when the temperature is raised, the transfer of the internal moisture in the materials will be substantially equal to the rate of evaporation of the moisture upon the exterior surface of the materials, thereby preventing case-hardening of the surface and cracking or checking by reason of internal steam pressure or other stresses heretofore occurring; to cause the internal moisture to rapidly leave or pass to the exterior

surface of the materials, under its own vapor tension as the temperature rises, the physical condition of the surface of the wares being maintained similar to that of the interior in so far as moisture content may be concerned, by the control of the condition 60 of the surrounding or enveloping fluid medium or gases; to greatly reduce the time required for drying and to obtain the objects above noted, by the subjecting of the materials to an enveloping mass or atmosphere of superheated steam; to carry out the above by a method of subjecting the materials, preferably in passages or tunnels of a drying kiln, or the like, whereby the materials are preferably caused to move or 65 travel progressively, to heat in excess of the temperature of the boiling point of water in a controlled humidified mass or volume of fluids or gases, which may be the hot products of combustion or the waste gases of 70 furnaces or the like, means being used to control the amount and the temperature thereof and also the quality of the humidity or the relative humidity, such that the fluids will absorb the surface moisture at substantially the same rate as that of the transfer 75 of the internal moisture to the surface of the materials; to provide novel means and apparatus for accomplishing these objects; to provide means for circulating, preferably 80 at different points of the travel of the materials, heated and humidified fluids or gases through and around the materials or wares; to provide means for supplying, preferably 85 at different points of travel of the materials, humidifying vapors, such as water spray or steam, or the like; to provide means for regulating, independently at each point, the quantity of humidifying matter; to provide means for recirculating part of the 90 heated and humidified fluids with the heated fluids being circulated by the circulating means; to provide means for regulating, at different points, the amount of fluids to be 95 recirculated, thus regulating or controlling the temperature and humidity of the fluids acting upon the wares or materials in the different parts of their travel through the kiln; and such other objects, advantages and capabilities as will later more fully appear and are inherently possessed by the invention.

In the accompanying drawings illustrat

ing a preferred form of kiln for carrying out the herein described process or method; Fig. 1 is a horizontal sectional view taken on substantially the floor level of the kiln; Fig. 2 is a longitudinal sectional view taken on line 2—2 of Fig. 1 of the drawings; Fig. 3 is a vertical longitudinal sectional view taken on line 3—3 of Fig. 1 of the drawings; Fig. 4 is a vertical longitudinal sectional view taken on line 4—4 of Fig. 1 of the drawings; Fig. 5 is a top plan view of the kiln and operating mechanism for operating parts thereof; Fig. 6 is a horizontal sectional view showing the upper portion of the kiln, partly in plan and partly in section; Fig. 7 is a transverse sectional view taken on line 7—7 of Fig. 1 of the drawings; Fig. 8 is a similar view taken on the line 8—8 of Fig. 1; Fig. 9 is a similar view taken on line 9—9 of Fig. 1; Fig. 10 is a broken horizontal sectional view, similar to Fig. 1, of a modification; Fig. 11 is a transverse sectional view of the same; and Fig. 12 is a similar view of a further modification.

Referring now more particularly to the drawings upon which is shown an illustrative embodiment of means, preferably in the form of a tunnel kiln, for carrying out the method herein disclosed, the wares or materials 1 are loosely packed upon cars 2 running over tracks 3 and 4 through a number of passages or tunnels 5, 6, 7 and 8, it being understood that the number of passages and tunnels is merely a matter of choice, as a lesser or larger number than that shown upon the drawings may be used. The cars 2 are preferably made to progress through each tunnel over the tracks 3 and 4 by any suitable means, such as a motor driven chain device 9 located in each ante chamber 10 and capable of engaging with the cars entering the ante chambers whereby the chain device causes a movement of the cars, and hence the train of cars ahead, so that the train will eventually pass or progress through the tunnel longitudinally thereof to the other end of the tunnel where the cars will pass to the exterior of the kiln after the wares or materials carried thereby have been treated. The ends of the tunnels may be closed, as desired, by doors 11 and 12, and suitable doors 13 may also be used between the ante chambers 10 and the tunnels.

Beneath the tunnels of the kiln, and near the ends thereof, are provided inlet and outlet cross ducts 14 and 15 for respectively conducting hot gases to and from the kiln.

The inlet cross duct 14 is connected at either or both ends to the source of heat, which may be by way of passing air or other gases through a furnace to absorb heat from the wares therein after the fire has been extinguished or diverted, or by way of drawing products of combustion from the

exhaust side of a furnace or the like, or the conveying of heated air or gases receiving their heat from the waste heat of furnaces, or the drawing of hot flue or stack gases and the like from the exhaust side of furnaces, as may be desired and found convenient to do. The outlets of cross conduit 15 may be connected at either or both ends to an exhaust device, which may have a blower and a stack capable of producing the required draft to draw the heated fluids through the kiln.

The cross duct 14 has a number of discharge ports 16 communicating with the tunnels near the outlet ends thereof for permitting a controllable amount of heated fluids to pass upwardly through the tunnels and the materials carried by cars passing therethrough. These ports are each controlled by any suitable dampers 17 or like devices which may be operated from the operating room above the kiln by pull-chains 18 or the like. See Fig. 2 of the drawings. The cross duct 15 also has inlet ports 15* communicating with the tunnels near the inlet ends thereof adjacent the outlets of the ante chambers whereby the gases in the tunnels, after having performed their functions, may be exhausted through the ports 15* into the duct 15 and carried away to the stack.

The duct 14 also communicates, by way of a lateral port, with longitudinal and centrally located gas chamber 19 which is preferably located between the two halves of the chamber, as clearly shown in Fig. 1 of the drawing. This chamber has a covering or roof 20 and is closed at its other end by a vertical wall 21. At intervals along the two sides of the roof 20 are provided ports 22 and 23 controlled by suitable gates or dampers 24 and 25 which may be operated by pull chains 26 and 27 capable of adjustment and operation from the operating room 28 located above the kiln, as clearly shown in Fig. 7 of the drawings.

Transversely beneath the tunnels at intervals are provided passages 29, 30, 31 and 32 respectively having outlet ports 33, 34, 35 and 36 respectively communicating with the interior of tunnels 3 and 4. The inlet ends of ports of these passages are respectively controlled by sliding gates or dampers 37 and 38 suitably connected to bars 39 and 40 which may be operated from the operating room 28, as clearly shown in Fig. 7 of the drawings. It will be noted that the ports 22 and 23 in the roof 20 are so located that they have easy communication with the adjacent pair of inlet ports to the passages 30 and 32, and 29 and 31 respectively, as clearly shown in Fig. 1 of the drawings.

Above the tunnels is provided a flooring having a plurality of outlet openings or ports 41 and 42 for the upward passage of the hot gases and vapors as they leave the

5 materials 1 on the cars, and pass into the upper chambers 43, 44, 45 and 46 extending longitudinally above each tunnel and communicating at the entry end of the tunnels with ports 47 and 48 for the down-flow of gases to the tunnels and into the cross duct 15 by way of the ports 15. By referring to Fig. 8 it will be noted that the ports 41 and 42 form a sort of 10 checker work in the flooring whereby the gases may pass easily upwardly and downwardly as hereinafter more fully described.

15 The chambers 43, 44, 45 and 46 also communicate laterally with a central longitudinal chamber 49 disposed above the chamber 19 and spaced therefrom. Between the chamber 19 and the chamber 49 is provided a longitudinal gas mixing chamber 50, the latter being separated from the chamber 49 20 by a wall 61 in which are provided, at intervals, rotary blowers or fans 52 suitably driven by power means located in the operating room 28, as clearly shown in Figs. 7 and 9 of the drawings. The mixing chamber 50 is located immediately above the roof 20, the latter being so shaped that the mixing chamber 50 may readily communicate with the cross passages 29, 30, 31 and 32, as well as with the chamber 19 by way of the 25 ports 22 and 23, as clearly shown in Fig. 7 of the drawings. The fans 52 may be rotated in either direction to cause a circulation of the hot gases and vapors through the mixing chamber 50 and through the cross 30 passages, then through the tunnels, then through the upper chambers and back again into the mixing chambers. This circulation is carried on together with the entry of gases from the chamber 19 as will be 35 explained more fully hereinafter.

40 In order that the hot gases or fluids supplied to the kiln may have the proper amount of humidity or moisture when the same reaches the wares or materials to be treated, several moisture supplying or spraying means may be provided at different parts of the kiln. In the ridge portion of the roof 20 is provided a spray pipe 53 which preferably extends longitudinally of the roof 20 and is capable of spraying water or steam into the chamber 50 to supply a sufficient quantity of moisture to the hot gases circulated therethrough. In the tunnels, preferably between the tracks, may also be provided similar spray means 54 and 55 as clearly shown in Fig. 7 of the drawing, so that humidity may be supplied to the incoming gases passing upwardly through the ports in the flooring of the tunnels. In the upper chambers 43, 44, 45 and 46 may also be provided similar spray means 56 and 57 for adding moisture, if desired, to the gases as they pass from the tunnels and are circulated through the fans 52 and the mixing chamber 50. Spray pipe 58 may also be

provided at intervals and to extend downwardly through the chamber 49 and capable of spraying steam or moisture just beneath the fans 52 in the mixing chamber 50. (See Figs. 7 and 8.) It is to be understood that means for supplying moisture may be supplied at any point desired throughout the kiln depending upon the convenience and the particular amount of moisture to be supplied. Each of these spraying devices are suitably controlled in any desired manner so that the amount of moisture can be varied as desired at the various points in the kiln.

Referring more particularly to Figs. 10, 11 and 12, the construction of the kiln is substantially the same as heretofore described with the exception that an additional conduit 60 is provided between the chambers 19 and 50. It has been found that if products of combustion were to be brought into direct contact with the wares, such products would have chemicals, such as sulphur and the like, which might have an effect of producing a coloration of the wares which would not be desirable. In order that the heat of the products of combustion may be utilized and the chemical action upon the wares avoided, the kiln may be constructed with the additional conduit 60 which has no communication with the passages of the kiln whereby any of the gases passing therethrough could have access to the wares, but this conduit is so located that it will conduct gases therethrough from its inlet end 61 to its outlet end 62 where it will discharge into the exhaust or outlet cross duct 15, in any convenient manner as clearly shown in Fig. 10 of the drawings. Inasmuch as these gases are usually of higher temperature than the other gases, the heat of radiation obtained therefrom through the walls of the conduit 60 may be absorbed and utilized. In order to help the radiating of the heat, the conduit 60 is preferably provided with a plurality of fins 63 so arranged and disposed that they will be in the path of the stream of gases circulated by the fans 52. The conduit 60 is so located with reference to chambers 19 and 50 that they will give heat to both the gases in the chamber 19 and to the gases and vapors in the chamber 50. Fig. 11 shows one form of this construction, and Fig. 12 is a similar form where the main supply of gases is from the upper part of the central chamber instead of from below. In the form shown in Fig. 12 the operating shaft of the fans 52, may if desired, extend the conduit 60 without any material leakage of gases from the conduit.

In operation the hot gases pass into the cross duct 14 and a small portion of these gases pass upwardly through the ports 16 into the tunnels, the amount thus passing up being controlled by the dampers 17. The main portion of the gas passes into

the central chamber 19 where it heats the roof 20 for giving radiated heat to the fluids in the mixing chamber 50. The fans 52 may be thrown into operation to circulate gases and vapors in the direction shown by the arrows, but it is to be understood that the circulation may be in the reverse direction if desired. The sliding gates 37 and 38 may be regulated as desired to control the circulation of the gases through the passages 29, 30, 31 and 32. Assuming that the dampers 24 and 25 are closed, it will be noted that the hot gases first enter into the tunnels through the ports 16 and pass upwardly into the upper chambers 43, 44, 45 and 46 from whence the fans 52 draw the gases and moisture and into the mixing chamber 50 to be recirculated again through the cross passages in the tunnels, as clearly shown in Fig. 7. It will be noted that the movement of the gases is in a sort of a spiral or helix in each side of the kiln, the gases progressing toward the other end of the kiln where they are finally exhausted through the ports 15^a and into the cross duct 15. While the gases are passing through the mixing chamber 50 they are increased in temperature by the radiating heat given off by the roof 20, or in the form of device shown in Figs. 10, 11 and 12, the radiating heat given off by the surface of the conduit 60, in addition to that which may be given off by the roof portion 20 connected between the conduit 60 and the side walls of the passage 19. If it be desired to add to the gas circulation, the dampers 24 and 25 may then be opened and regulated to the desired amount to receive or bleed in additional amount of hot gases. In this way the amount of gases may be regulated with reference to the amount of moisture supplied thereto so that the relative humidity of the gases is such that the transfer of moisture from the surface of the wares or materials in the tunnels will be substantially the same or slightly greater than the transfer of moisture from the interior of the ware so that there will not be a cracking or checking of the surface of the ware by the too rapid transfer of moisture from the interior thereof to the exterior.

While we have herein shown one direction of circulation by arrows in Fig. 7 of the drawing, it is to be understood that the invention comprehends the circulation of gases in either direction as desired and depending upon the convenience of operating the kiln. This is also true as to the forms shown in Figs. 10, 11 and 12.

The various parts of the device may be operated from an operating room located above the furnace and including suitable power operating machinery for carrying out the desired result. Such machinery may comprise a motor belted to a shaft 65

which in turn is connected to the fans by belts 66 and also by belts 67 to a mechanism for operating the chain device 9 in the ante chambers of the kiln.

As the mixture of gases and vapors pass toward the end of the kiln they pass downwardly through the ports 15^a and into the cross duct 15 and thence to an exhaust device or stack whereby they pass off to the atmosphere. It will thus be seen that as the wares or materials enter the tunnels, they first come into contact with a mixture of heated gases and vapors highly charged with moisture but lower in temperature than the wares will be later subjected to as they progress through the tunnels. Upon leaving the tunnels and after all of the moisture has been extracted from the wares, the wares are now subjected to a dry hot fluid for completion of evaporation of all moisture from the wares so that the wares are discharged from the kiln in dry state.

While we have herein described and shown upon the drawings a few embodiments of the invention, it is to be understood that the invention is not limited to the particular arrangement of parts, details and constructions described and shown, but that it also comprehends other arrangements of parts, constructions, and details, without departing from the spirit of the invention.

Having thus described our invention, we claim:

1. A method of drying refractory ware, comprising moving the ware through a heating and humidifying medium, the ware being subjected to increasing temperatures and decreasing humidities during said movement of the ware through said medium, causing a general travel of said medium in a direction opposite to the travel of the ware, and forcing said medium at successive points vertically through said ware.

2. A method of drying refractory ware, comprising moving the ware through a heating and humidifying medium, the ware being subjected to increasing temperatures and decreasing humidities during said movement of the ware through said medium, forcing a portion of said medium in a direction opposite to that of the movement of the ware, forcing another portion of the medium vertically through said ware, and feeding regulated amounts of said medium from said first mentioned portion to said second mentioned portion.

3. A method of drying refractory ware, comprising moving the ware through a heating and humidifying medium, the ware being subjected to increasing temperatures and decreasing humidities during said movement of the ware through said medium, forcing a portion of said medium in a direction opposite to that of the movement of the ware, forcing another portion of the medium ver-

tically through said ware, and feeding regulated amounts of said medium from said first mentioned portion to said second mentioned portion, and subjecting said first portion to radiant heat.

4. A method of drying refractory ware, comprising moving the ware through a tunnel of a kiln or the like, forcing a heating medium through a passage in said kiln in a direction opposite to the direction of movement of the ware in the kiln, diverting regulated portions of said medium from said passage at successive points into and through said ware at successive points thereof.

15 5. A method of drying refractory ware, comprising moving the ware through a tunnel of a kiln or the like, forcing a heating medium through a passage in said kiln in a direction opposite to the direction of movement of the ware in the kiln, diverting regulated portions of said medium from said passage at successive points into and through said ware at successive points thereof.

20 6. A method of drying refractory ware, comprising moving the ware through a tunnel of a kiln or the like, forcing a heating medium through a passage in said kiln in a direction opposite to the direction of movement of the ware in the kiln, diverting regulated portions of said medium from said passage at successive points into and through said ware at successive points thereof, leading the diverted amounts of said medium to 25 points where humidity may be applied, and supplying regulated amounts of humidity to said diverted amounts of said medium.

30 7. A method of drying refractory ware, comprising moving the ware through a tunnel of a kiln or the like, forcing a heating medium through a passage in said kiln in a direction opposite to the direction of movement of the ware in the kiln, diverting regulated portions of said medium from said 35 passage at successive points into and through said ware at successive points thereof, and leading each of said diverted amounts of said medium after passing through a point of the ware to and through a succeeding point of 40 the ware and in the same direction through said ware as it previously passed through the previous point of said ware.

45 8. A kiln for drying wares, comprising a tunnel for the passage therein of the ware to be treated, a gas chamber extending along the side of the tunnel, a mixing chamber extending along the side of the gas chamber, and admission chambers located above and below the tunnel, said admission chambers 50 having series of ports located for the passage of hot gases from the gas chamber to the mixing and admission chambers and through the ware in the tunnel.

55 9. A kiln comprising a passage for the movement of ware therethrough, admission chambers above and below said passage and having ports of communications between said passage and said admission chambers, a mixing chamber having ports of communication 60 with said admission chambers, and means for conducting a treating medium with said mixing chamber.

65 10. A kiln comprising a passage for the movement of ware therethrough, admission chambers above and below said passage and

having ports of communications between said passage and said admission chambers, a mixing chamber having ports of communication with said admission chambers, means for regulating the size of said ports at will, 70 and means for conducting a treating medium into said mixing chamber.

110 11. A kiln comprising a passage for the movement of ware therethrough, admission chambers above and below said passage and having ports of communication between said passage and said admission chambers, a mixing chamber having ports of communication with said admission chambers, a duct below said mixing chamber, said duct having a plurality of ports communicating with said mixing chamber at different points, and means for conducting hot gases into said duct.

80 11. A kiln comprising a passage for the movement of ware therethrough, admission chambers above and below said passage and having ports of communication between said passage and said admission chambers, a mixing chamber having ports of communication with said admission chambers, a duct below said mixing chamber, said duct having a plurality of ports communicating with said mixing chamber at different points, means for controlling said ports, and means for conducting hot gases into said duct.

85 12. A drying means for refractory materials, comprising kiln passages through which the materials are moved, means for moving the materials, means for conducting heated gases to said passages, means for circulating the gases through the materials, and means for withdrawing the circulated gases.

100 13. A kiln having tunnels, means for moving refractory material along said tunnels, gas inlets and outlets in said tunnels, means controlling the flow of gas into the tunnels, and means for recirculating part of the gases flowing from the tunnels.

105 14. A kiln having tunnels, means for moving refractory materials along said tunnels, gas inlets and outlets in said tunnels, means controlling the flow of gas into the tunnels, and means in said tunnels for supplying humidity to said gas.

110 15. A kiln having tunnels, means for moving refractory material along said tunnels, gas inlets and outlets in said tunnels, means controlling the flow of gas into the tunnels, and means located at intervals in said tunnels for forcing moisture into said gas circulated through said tunnels.

115 16. A kiln having tunnels, means for moving refractory material along said tunnels, gas inlets and outlets in said tunnels, means controlling the flow of gas into the tunnels, and means located adjacent the inlets of said tunnels for supplying water vapor to the gas flowing into said tunnels.

17. A kiln having tunnels, means for moving refractory materials along said tunnels, gas inlets and outlets in said tunnels, means controlling the flow of gas into the tunnels, means located adjacent the inlets for supplying water vapor to the gas flowing into said tunnels, and means for regulating the amount of water vapor supplied at each of said inlets.
18. A drying kiln for refractory materials, passages for the materials, means for moving the materials through said passages, means for circulating heated and humidified gases through the materials in the passages, and means for recirculating part of the circulated gases with the incoming gases at successive points beyond the previous points of circulation of the gases.
19. A drying kiln for refractory materials, tunnels, means for moving the materials through the tunnels, means for heating the materials above the boiling point of water, means for supplying at successive points in said tunnel moisture to the exterior surface of the materials at a rate substantially equal to the rate of evaporation on the surface of the materials.
20. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation at successive points in advance of the previous points of admission, and means for controlling said recirculation.
21. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation, means for controlling said recirculation, and means cooperating with the admitting means for supplying given amounts of water vapor.
22. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation, means for controlling said recirculation, and means cooperating with the admitting means for supplying given amounts of water vapor.
23. A kiln comprising a passage for the movement of ware therethrough, admission chambers above and below said passage and having ports of communication between said passage and said admission chambers, a mixing chamber having ports of communication with said admission chambers, blowers in said mixing chamber and between the upper and lower ports of communication from said admission chambers, whereby circulation of the medium in said chambers may be effected in a vertical direction through said ware, and means for conducting a treating medium into said mixing chamber.
24. A kiln comprising a passage for the movement of ware therethrough, admission chambers above and below said passage and having ports of communication between said passage and said admission chambers, a mixing chamber having ports of communication with said admission chambers, spray means located in said mixing chambers and in said admission chambers at different points for the distribution of moisture therein, and means for conducting a heating medium into said mixing chambers.
25. A kiln comprising a passage for the movement of ware therethrough, admission chambers above and below said passage and having ports of communication between said passage and said admission chambers, a mixing chamber having ports of communication with said admission chamber, heating means extending through said mixing chamber for effecting radiant heating of the medium in the mixing chamber, and means for conducting a heating medium of one temperature into said mixing chamber and of a higher temperature into said heating means.
26. A kiln comprising a passage for the movement of ware therethrough, admission chambers above and below said passage and having ports of communication between said passage and said admission chambers, a mixing chamber having ports of communication with said admission chambers, a checker work in said admission chambers for effecting distribution of the heating medium, and means for conducting a heating medium into said mixing chamber.

In witness whereof, we hereunto subscribe our names to this specification.

WILLIAM E. WILSON.
HENRY G. LYKKEN

17. A kiln having tunnels, means for moving refractory materials along said tunnels, gas inlets and outlets in said tunnels, means controlling the flow of gas into the tunnels, means located adjacent the inlets for supplying water vapor to the gas flowing into said tunnels, and means for regulating the amount of water vapor supplied at each of said inlets.
18. A drying kiln for refractory materials, passages for the materials, means for moving the materials through said passages, means for circulating heated and humidified gases through the materials in the passages, and means for recirculating part of the circulated gases with the incoming gases at successive points beyond the previous points of circulation of the gases.
19. A drying kiln for refractory materials, tunnels, means for moving the materials through the tunnels, means for heating the materials above the boiling point of water, means for supplying at successive points in said tunnel moisture to the exterior surface of the materials at a rate substantially equal to the rate of evaporation on the surface of the materials.
20. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation at successive points in advance of the previous points of admission, and means for controlling said recirculation.
21. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation, and means cooperating with the admitting means for supplying given amounts of water vapor.
22. A drying kiln for refractory materials, a tunnel, means for moving the materials through the tunnel, means for admitting heated fluids into the tunnel at different points, outlets for the fluids, means for redirecting part of the outgoing fluids to the admitting means for recirculation, means for controlling said recirculation, and means cooperating with the admitting means for supplying given amounts of water vapor,
23. A kiln comprising a passage for the movement of ware therethrough, admission chambers above and below said passage and having ports of communication between said passage and said admission chambers, a mixing chamber having ports of communication with said admission chambers, blowers in said mixing chamber and between the upper and lower ports of communication from said admission chambers, whereby circulation of the medium in said chambers may be effected in a vertical direction through said ware, and means for conducting a treating medium into said mixing chamber.
24. A kiln comprising a passage for the movement of ware therethrough, admission chambers above and below said passage and having ports of communication between said passage and said admission chambers, a mixing chamber having ports of communication with said admission chambers, spray means located in said mixing chambers and in said admission chambers at different points for the distribution of moisture therein, and means for conducting a heating medium into said mixing chambers.
25. A kiln comprising a passage for the movement of ware therethrough, admission chambers above and below said passage and having ports of communication between said passage and said admission chambers, a mixing chamber having ports of communication with said admission chamber, heating means extending through said mixing chamber for effecting radiant heating of the medium in the mixing chamber, and means for conducting a heating medium of one temperature into said mixing chamber and of a higher temperature into said heating means.
26. A kiln comprising a passage for the movement of ware therethrough, admission chambers above and below said passage and having ports of communication between said passage and said admission chambers, a mixing chamber having ports of communication with said admission chambers, a checker work in said admission chambers for effecting distribution of the heating medium, and means for conducting a heating medium into said mixing chamber.

In witness whereof, we hereunto subscribe our names to this specification.

WILLIAM E. WILSON.
HENRY G. LYKKEN.

Certificate of Correction.

It is hereby certified that in Letters Patent No. 1,570,659, granted January 26, 1926, upon the application of William E. Wilson, of Mason City, Iowa, and Henry G. Lykken, of Minneapolis, Minnesota, for an improvement in "Methods of and Apparatus for Drying Refractory Materials," an error appears in the printed specification requiring correction as follows: Page 3, line 123, after the word "extend" insert the word *through*; and that the said Letters Patent should be read with this correction therein that the same may conform to the record of the case in the Patent Office.

Signed and sealed this 23d day of March, A. D. 1926.

[SEAL.]

M. J. MOORE,
Acting Commissioner of Patents.
